(57) **CLAIM**

The ornamental design for an intelligent service robot as shown and described.

DESCRIPTION

The patent or application file contains at least one drawing executed in color. Copies of this patent or patent application publication with color drawing(s) will be provided by the Office upon request and payment of the necessary fee.

1. Intelligent service robot

1.1 : Front perspective view

1.2 : Back perspective view

1.3 : Front view

1.4 : Back view

1.5 : Left view

1.6 : Top view

1.7 : Bottom view

1.8 : Cross sectional view

1.9 : Reference view

The characteristic features of the design lie in the combination of the shape and pattern; the omitted right view is a mirror image of the left view; reproduction 1.8 is a horizontal cross-sectional view of reproduction 1.3; the broken lines shown in reproductions 1.1 to 1.7 depict portions of the intelligent service robot and form no part of the claimed design; reproduction 1.9 shows the claimed design in its environment of use, wherein all other broken lines and colors illustrate environmental structures that form no part of the claimed design; the shading lines are used to show the surface of the claimed design and do not represent its surface ornamentation.
